UNITED STATES PATENT OFFICE

FRANK E. DE LONG, OF WASHINGTONVILLE, PENNSYLVANIA

BOTTLE STOPPER

Application filed October 22, 1931. Serial No. 570,360.

This invention relates to stoppers for bottles, jars and similar receptacles, and it has reference more particularly to stoppers made from compressible material like cork.

5 Ordinarily cork bottle stoppers are apt to become dislodged incident to shaking of the contents of the bottles, the foregoing being especially true when the contents are of an oily or slippery nature and prevent the 10 stoppers from taking effective hold upon the insides of the bottle necks.

The object of my invention is to preclude the possibility of the contingency above pointed out; and this desideratum I attain 15 as hereinafter fully explained through provision on the stopper of a lateral pin projection adapted to engage with an internal circumferential groove within the neck of the bottle, thereby to positively hold the 20 stopper in place with the latter in leak-tight circumferential compression.

In the drawing, Fig. I is an illustration partly in elevation and partly in section, showing a typical bottle fitted with my improved stopper; and,

Fig. II is a perspective view of the neck portion of the bottle.

The bottle chosen for convenience of illustration herein has a square body 3, and a 25 reduced cylindric neck 4 centrally of its top. The stopper indicated at 5 is of the slightly tapered type, and, it is to be understood, made of a compressible material like cork.

35 In adapting such a stopper 5 to the purposes of my invention, I run diametrically through it, a pin 6 of such length as to provide a lateral lug projection 7 beyond said stopper at one side. As shown, I force the head 8 of the pin 6 somewhat into the stopper 5 so that it may serve as an anchorage to secure said pin against displacement.

In order to adapt the bottle 3 for use of a 45 stopper 5 modified as just explained, I form the neck 4 of said bottle with a series of internal grooves for selective engagement by the lug 7 of the stopper 5, there being in the present instance three such grooves indicated respectively by the numerals 9, 10 and 50 11, said grooves being accessible by way of

an entrant notch 12 extending downward from the mouth of the bottle neck 4 to the lowermost groove 11.

Incident to initial application of the 55 stopper 5, the lug projection 7 is registered with the notch 12 in the bottle neck 4 and the stopper 5 forced in until its lug 7 registers with the first groove 9 of the series 9-11. The stopper 5 is therupon turned in one direction or the other to bring the 60 lug 7 into the groove 9. As the stopper 5 wears, or takes a permanent set, it is forced further inward so that the lug 7 is engaged with either the groove 10 or the groove 11 as may be required to insure a leak-tight 65 closure. In any event, through my invention, the stopper 5 is effectively locked against dislodgment incident to shaking of the contents of the bottle 3, and it is especially advantageous in preventing slipping 70 of the stopper 5 when the bottle contents are of an oily nature.

Having thus described my invention, I claim:

1. The combination with a bottle having 75 a series of internal circumferential-grooves spaced longitudinally in the neck thereof, of a stopper made from compressible material like cork and having a lateral lug projection adapted to engage either of said internal circumferential-grooves in the bottle neck for positive retainment of the stopper against accidental dislodgment, the said 80 grooves having an entrant notch downward from the bottle mouth for passage of the 85 projection on the stopper incident to application of the latter.

2. The combination with a bottle having a series of internal circumferential-grooves spaced longitudinally in the neck thereof, of 90 a stopper made from compressible material like cork and having a pin run diametrically therethrough with provision of a lug projection, beyond the stopper at one side, 95 adapted to engage either of said internal circumferential-grooves in the bottle neck for positive retainment of the stopper against accidental dislodgment, the said grooves having an entrant notch downward 100 from the mouth of the bottle for passage of

the lug projection on the stopper incident to application of the latter.

3. In combination a bottle having a square body with a reduced cylindrical neck and a series of internal circumferential-grooves therein, a stopper made from compressible material like cork, having a headed-pin diametrically of the stopper with its head embedded therein and the point extended to one side thereof to provide a lateral projection adapted for selective engagement with said grooves to positively retain the stopper against dislodgment, and said grooves having in common an entrant notch downward from the bottle mouth to the lowermost groove for passage of the pin projection on the stopper incident to application of the latter.

4. The combination with a resilient and compressible tapered bottle stopper having its larger end uppermost so as to be progressively compressed to a smaller diameter when inserted further and further into a bottle, and having a laterally projecting locking member; of a bottle with a mouth smaller than the larger end of said stopper, and with a plurality of locking grooves at different heights relative to its mouth, selectively engageable by said lug according to the degree of insertion of the stopper and its extent of consequent compression.

In testimony whereof, I have hereunto signed my name at Philadelphia, Pennsylvania, this 20th day of October 1931.
